UNITED STATES PATENT OFFICE.

JOHN TOOMEY AND JOSEPH OLDHAM, OF NORTH ADAMS, MASSACHUSETTS.

SQUARE AND MITER DEVICE.

1,270,464.

Specification of Letters Patent. Patented June 25, 1918.

Application filed May 23, 1917. Serial No. 170,480.

To all whom it may concern:

Be it known that we, JOHN TOOMEY and JOSEPH OLDHAM, citizens of the United States, residing at North Adams, in the county of Berkshire and State of Massachusetts, have invented certain new and useful Improvements in Square and Miter Devices, of which the following is a specification.

10 This invention has to do with carpentry implements and is in the nature of a combination device embodying two of the tools most generally used by carpenters. The invention consists of a combination square, 15 comprising a try-square and a foot-rule, and means for holding the latter on the try-square so as to enable the implement to be used either as a square or bevel for mitering and other purposes, or as an extension to 20 obtain a straight-edge prolongation of a leg of the square.

The objects and advantages of this invention are obtained by the combination and arrangement of parts as hereinafter more 25 fully described, claimed and illustrated in the accompanying drawings, wherein:

Figure 1 is a plan view of the try-square element of this device;

Fig. 2 is an edge view of the same, showing more clearly the clamping flange;

Fig. 3 is an end view of the square;

Fig. 4 is a plan view showing the application of the foot-rule element to the square to produce an extension of the leg of the 35 square;

Fig. 5 is an end view of the implement as shown in Fig. 4; and

Fig. 6 is a plan view showing the rule clamped in a position to permit the movable 40 section of the rule to coöperate with a leg of the square for beveling purposes.

Specifically describing the invention and referring to the drawings, it will be observed that the device comprises two main elements, namely, the try-square 1 and the foot-rule 2, both of which are conventional in formation, excepting only that the shorter of the legs of the square is provided at one edge with a flange 3 and a clamping member 50 in the form of a cam lever 4 pivotally attached to the leg in spaced relation to the flange aforesaid.

We preferably employ for our purposes a two-foot rule embodying pivoted sections,

such being essential to fully carry out the 55 objects of this invention.

Referring to Figs. 4 and 6, respectively, the two main uses of this combination implement will be noted, the first of said figures disclosing the extension function and 60 the second its arrangement for constituting a bevel, as employed in marking studding for hip roof construction, or for mitering, etc.

The shorter of the legs of the square is preferably constructed to be of the same 65 width as the two legs of the foot rule when placed side by side, as in Fig. 4 and the lever 4 is so mounted on this leg as to enable the disposition of one of the rule legs between it and the flange 3, whereupon 70 swinging of the lever around on its pivot will clamp the rule against the flange and firmly hold this rule in place. The lever is purposely made thin so that the other leg of the rule will lie upon the same, as 75 shown in Fig. 5, the outer edge of the rule being flush with the outer edge of the square. The shorter of the legs of the square when the rule is thus attached is prolonged and the implement is particu- 80 larly useful in stair building as thus arranged.

Releasing and turning the rule from the position shown in Fig. 4 to that of Fig. 5 and again clamping said rule, the free leg 85 thereof may now be swung in a direction longitudinal of the longer of the legs of the square so as to obtain the proper angle from the plane of the other leg of the square. This longer leg of the square is 90 suitably graduated, as indicated at 5 so as to provide a guide for the workman in securing the desired angle.

The uses of this simple invention will readily appear to those acquainted with 95 carpentry and the fact that the implement is made up of two of the tools which form a part of the necessary equipment is especially advantageous, as they are capable of either conjoint or separate and independ- 100 ent use.

Having thus described our invention, what we claim as new is:—

A combination tool of the class described consisting of a body member having arms 105 arranged at an angle to each other, a second member adapted to be attached to one of said arms to provide an extension there-

for, said second member consisting of a relatively stationary section and a freely movable section arranged for coöperation with the other of said arms of the body member for determining the angle with respect thereto, said other body member arm being provided with graduations with which the freely movable section coöperates,

and clamping means on said first mentioned body member arm for holding the extension member in place thereupon.

In testimony whereof we affix our signatures.

JOHN TOOMEY.
JOSEPH OLDHAM.
